UNITED STATES PATENT OFFICE

JOSEPH L. WALKER, OF BATON ROUGE, LOUISIANA

CARBURETOR

Application filed February 6, 1928. Serial No. 86,557.

This invention relates to carburetors, one of the objects being to provide a simple and compact structure, the parts of which can be readily separated for the purpose of cleaning and repairing them.

5 A further object is to provide a carburetor utilizing a rotary valve which can be shifted at will to regulate the amount of mixture delivered from the carburetor, the construction and operation of the valve being such 10 as to proportionately increase or reduce the flow of air and fuel when the mixture delivered from the carburetor is increased or reduced in volume.

15 With the foregoing and other objects in view which will appear as the description proceeds, the invention resides in the combination and arrangement of parts and in the details of construction hereinafter described 20 and claimed, it being understood that changes in the precise embodiment of the invention herein disclosed may be made within the scope of what is claimed without departing from the spirit of the invention.

25 In the accompanying drawings the preferred form of the invention has been shown.

In said drawings,

Figure 1 is a top plan view of the carburetor.

30 Figure 2 is a side elevation thereof.

Figure 3 is a section on line 3—3 Figure 1.

Figure 4 is a section on line 4—4 Figure 2.

Figure 5 is a section on line 5—5 Figure 3.

Figure 6 is a section on line 6—6 Figure 3.

35 Figure 7 is a view partly in elevation and partly in section showing more or less in diagram the cooperating ports in one side portion of the carburetor.

Figure 8 is a perspective view of the nozzle sleeve.

40 Referring to the figures by characters of reference 1 designates the casing of the carburetor provided with an air intake passage 2 and an outlet passage 3, the two passages 45 being preferably in alignment and spaced apart by a substantially cylindrical intermediate portion 4 the bottom of which is recessed as at 5 so as to provide a circular seat. A partition 6 partially closes communication 50 between the interior of the central portion 4

and the inlet passage 2 while another partition 6' partially closes communication between the outlet passage 3 and the intermediate portion 4. As shown particularly in Figures 5, 6 and 7 the lower edges of these partitions are inclined so that each of the partitions overhangs the opening through which communication is established between the central portion 4 and the adjacent passages 2 or 3.

55 Mounted for rotation within the intermediate portion 4 of the casing is a cylindrical valve 7 within diametrically opposed portions of which are formed ports 8 and 9 adapted to communicate with the passages 2 and 3 respectively. As shown particularly in Figure 7 the port 8 has an inclined advancing wall 10 so that the port is wider at the bottom than at the top. It might be stated that the port 9 is of the same shape and arrangement as the port 8. Thus it will be seen that when valve 7 is rotated the widest portion of each of the ports 8 and 9 will first register with the lowermost portion of the opening or port 11 or 12 formed beneath adjacent partition 6 or 6'. As the inclined edges 6 and 10 are pitched in opposite directions respectively, it will be obvious that during this relative movement of the valve while being turned in one direction the clearance 60 between the crossed inclined edges of the ports 8 or 9 and 11 or 12 will be gradually increased both in width and height. In this connection attention is called to Figure 7.

65 The top of the valve 7 is closed by an integral cap 13 provided with an annular flange 14. Formed beneath this flange are lugs 15 adapted to ride upon inclined cam surfaces 16 located upon the intermediate portion 4 of the casing 1 at diametrically opposed points. An arm 17 is extended from the cap 13 and constitutes means whereby the cap and the valve 7 can be rotated for the purpose of controlling the flow of air and gas through the ports as heretofore explained. It will 70 be obvious that when the cap is turned in one direction for opening the ports the lugs 15 will ride upwardly on the cam surfaces 16, thereby causing the valve 7 to shift longitudinally as well as rotate. When the cap 75

- 13 is rotated in the opposite direction, this motion will be reversed, the valve moving longitudinally back to its initial position while, at the same time, the ports are gradually closed.
- 5 The bottom of the recess 5 is provided with a drain opening 18 for carrying off surplus liquid fuel. A nipple 19 is provided at the center of this recess and has a passage 20 extending therethrough. The upper end of the passage is flared as at 21 to provide a valve seat while the lower end of the passage is also flared as at 22 to provide a seat for a tapered plug 23 ground or otherwise properly fitted to its seat so as to provide a sufficiently tight connection. This plug is provided with one or more wings 24 whereby it can be removed readily from its seat 22. A passage 20 within the nipple communicates with a laterally extending passage 25 formed within a tubular arm 26 extending laterally from the intermediate portion 4 of the carburetor casing. A fuel supply pipe, not shown, is adapted to be coupled to this arm 26.
- 25 A tube 27 is disposed within the intermediate portion of the carburetor casing and has its counterbored lower end 28 fitted snugly upon the nipple 19. This tube is concentric with the valve 7 and has its upper end terminating close to the cap 13 of the valve. The tube constitutes a nozzle adapted to communicate with the passage 20 and formed within this tube at different elevations are small ports or vents 29 through which liquid fuel is adapted to be delivered in jets into the mixing chamber 30, which is the space surrounded by the valve 7.
- 40 A screw 31 is extended through the middle portion of the cap 13 and has a head 32 at its outer end. A stem 33 projects from the other end of the screw and is located within the tube 27, this stem being provided at its free end with a needle valve 34 normally engaging the seat 21.
- 45 For the purpose of holding the parts of the carburetor properly assembled a relatively stiff spring wire 35 is arranged outside of the casing 1 with its end portions turned inwardly toward each other. One of these end portions, 36, is seated within a recess 37 in the outer end of plug 23 while the other end portion 36 is seated within a recess 38 formed in the middle portion of the head 32. Thus the spring serves to hold the valve 7 pressed yieldingly into the casing while at the same time plug 23 is held firmly to its seat.
- 50 The screw 31 is adapted to be adjusted so that when the ports 8, 9, 11 and 12 are closed, valve 34 will be in engagement with its seat 21. Thus it will be seen that by rotating valve 7 as heretofore explained it will not only open the ports 8, 9 and 11 and 12 but the action of the lugs 15 on the cam faces 55 16 will result in the valve being slid or shifted longitudinally so as thereby to lift valve 34 off of its seat 21 and permit a predetermined amount of liquid fuel to enter the reservoir provided by the tube 27. Thus fuel will rise within the tube 27 and a small amount will be initially delivered through the lowermost ports 29, this amount being the correct quantity to be mixed with the volume of air initially admitted through the partly opened ports 8, 9, 11 and 12. As the opening of these last named ports is continued, thereby admitting a greater quantity of air to the mixing chamber 30 and delivering a greater amount of the combustible mixture to the passage 3, the supply of liquid fuel admitted to the tube 27 will be increased by the further opening of valve 34 so that fuel can not only be delivered from the lowermost ports 29 but will rise and be delivered from ports at higher levels. Thus as the amount of fuel is increased the number of ports 29 through which it is delivered is increased and the liquid fuel thus delivered into the mixing chamber will be thoroughly commingled with the air admitted thereto. The arrangement of the ports and valves is such that this mixture will always be in proper proportions irrespective of the amount of air and fuel being supplied to the mixing chamber.
- 55 It will be noted that the jets of liquid fuel are delivered transversely of the path of travel of the air flowing through the carburetor, thus insuring a better mixture of the liquid fuel with the air than would be possible should the liquid fuel be delivered along lines substantially parallel with the direction of the flow of the air.
- 60 For the purpose of locking the screw 31 adjustably to the cap 13 a lock nut 39 is mounted on the screw and bears firmly against the cap.
- 65 By removing spring 35 the valve 7 can be lifted readily out of the casing 1, tube 27 can be removed, plug 23 can be withdrawn from its seat 22 and the entire carburetor structure can thus be readily cleaned or repaired without requiring special tools or tools of any kind.
- 70 Any surplus liquid fuel that may accumulate within the mixing chamber is free to flow outwardly through the vent 18 through a pipe, not shown, to a fuel container.
- 75 What is claimed is:
- 80 In a carburetor a casing, a combined throttle valve and mixing chamber mounted to slide and rotate therein, said casing having an air inlet and an outlet, there being ports within the casing and throttle valve for establishing communication between the mixing chamber and the inlet and outlet of the casing, a tubular nozzle fixedly housed within the valve and having superposed outlet ports, a valve for controlling the flow of fuel to said nozzle, said throttle valve, when operated to slide and rotate in one direction, con-

stituting means for opening the fuel controlling valve, thereby to increase the flow of fuel in proportion to the increase in the flow of air to the mixing chamber, the number 5 of the ports in the nozzle through which the liquid fuel is delivered increasing as the amount of fuel is increased in the nozzle, a fuel supply passage leading to the fuel controlling valve and having an opening, a 10 tapered plug constituting a closure for said opening, and a spring yoke embracing the carburetor casing and having its terminals extended toward each other, one of said terminals bearing against the plug and the other 15 terminal exerting a pressure against the throttle valve, thereby to hold the plug and throttle valve firmly to their seats.

In testimony that I claim the foregoing as my own, I have hereto affixed my signature.

20 JOSEPH L. WALKER.
